Des. 188,652
Patented Aug. 23, 1960

188,652

MASQUERADE COSTUME

Anthony B. Laganella, 1824 Dudley St., and Charles E. McMenamin, 554 Acorn St., Philadelphia, Pa.

Filed July 28, 1959, Ser. No. 56,970

Term of patent 14 years

(Cl. D3—17)

We claim:

The ornamental design for a masquerade costume, as shown.
